UNITED STATES PATENT OFFICE.

WILLIAM P. ROBERTSON, OF NEW YORK, N. Y.

CUTTING INSTRUMENT.

1,287,754.

Specification of Letters Patent. Patented Dec. 17, 1918.

Application filed April 15, 1915. Serial No. 21,597.

To all whom it may concern:

Be it known that I, WILLIAM P. ROBERTSON, a citizen of the United States, and a resident of the city of New York, borough 5 of Manhattan, county and State of New York, have invented a new and Improved Cutting Instrument, of which the following is a specification.

My invention relates generally to cutting instruments having two or more pivotally connected cutting blades. It is particularly applicable to cutting instruments adapted to perform comparatively heavy work.

One of the objects of my invention is to provide a cutting instrument in which at least one of the shearing or cutting blades has an irregular or scalloped cutting edge or edges, the cutting instrument being so constructed that there will be a relative longitudinal movement between co-acting blades, as the instrument is operated.

Another object of my invention is to provide a cutting instrument comprising two coöperating blade members pivotally connected together, so constructed and arranged that there will be a relative longitudinal movement of one of the blade members rearwardly toward the handles so that the material being sheared will be forced or drawn 20 toward the angle formed by the two cutting blades.

Another object of my invention is to provide a cutting instrument having a pair of outer pivotally-connected blades and having a blade provided with irregular or scalloped cutting edges on opposite sides thereof located between said outer blades, the irregular or scalloped edges coöperating with the cutting edges of the co-acting outer 30 blades.

Another object is to provide a cutting instrument having a pair of outer pivotally-connected blades and a cutting blade located between them, the instrument being so constructed that there will be a relative longitudinal movement between the central blade and each of the outer blades, as the instrument is operated.

Other and further objects of my invention 40 will clearly appear from the detailed description to follow.

As showing a specific embodiment of the invention reference is made to the drawing

forming a part of this specification, in which drawing,

Figure 1 shows in plan a pair of hedge-trimmers or shears embodying the invention. In said figure the full lines show the shears in open position, while the dotted lines indicate the position of the various 55 parts when the shears are closed.

Fig. 2 is a side elevation of a portion of the cutting blades and their operative connections.

Fig. 3 is an enlarged plan view showing 60 a portion of the intermediate shear blade with its irregular or scalloped edges.

Fig. 4 is a transverse sectional view showing the relative positions of the several cutting blades when in closed position.

Fig. 5 shows a portion of a modified form 65 of the intermediate cutting blade.

Fig. 6 shows a portion of the connecting means between the handle portion of the outer blades and the intermediate blade 70 shown in Fig. 5; and

Fig. 7 shows a portion of another modified form of the lower end of the intermediate blade and its operative connections.

The outer blade members A and B are pivotally connected together by the bolt or pivot pin C. These outer blade members A and B comprise the blade proper a and b and the handle portion or stem a' b', upon which are driven or otherwise fixedly secured the handles proper D and E. The shears also comprise an intermediate blade F, upon the opposite edges of which, namely, along the edges G and H, are the irregular or scalloped cutting portions 75 80 85 90 95 which coöperate respectively with the cutting edges M and L.

In the embodiment of my invention illustrated in Fig. 1, this intermediate blade is slotted, as at N, to receive the filler-piece or member c' adapted to slide freely in the slot N. The filler-piece c' is perforated so as to permit the bolt or pivot pin C to pass therethrough. The intermediate blade F is also provided with a rearwardly extending portion O. This rearwardly extending portion O is pivotally connected through the medium of the links P and Q to the handle portions a' and b' respectively, the link P being connected to extension O by the bolt 100 105 or pivot pin K and to the handle portion a'

by the bolt or pivot pin S, and the link Q being connected to extension O by the bolt or pivot pin K and to the handle portion b' by the bolt or pivot pin T.

- 5 As shown in Fig. 1, it is apparent that as the blades A and B are caused to approach the intermediate blade F, the links P and Q will cause the intermediate blade to simultaneously move longitudinally relative 10 to the blades A and B. This longitudinal relative movement is enabled to take place due to the filler piece c' sliding freely in the slot N. As the bolt or pivot pin C passes through the filler-piece c', the intermediate 15 blade F will be always maintained substantially in its central position between the outer cutting blades.

In the embodiment of my invention as illustrated, the outer blades A and B are 20 provided with regular or straight cutting edges L and M respectively, while the intermediate blade F is provided with irregular or scalloped cutting edges G and H. It will be noted that as the outer blades A and 25 B approach the intermediate blade F, the latter is forced longitudinally rearwardly, so that the pieces of material being sheared will tend to be forced toward the angle formed by the cutting edges and thus prevented 30 from slipping forwardly toward the free ends of the cutting blades. Moreover, the rearward movement of the intermediate blade coacting with the outer blades will give a draw or shearing cut, which is a 35 highly desirable feature in instruments of this kind.

Two modified forms of my invention are shown in Figs. 5, 6 and 7. In these two forms the intermediate blade F does not 40 have the longitudinal movement rearwardly relative to the coöperating outer blades, but the intermediate blade is maintained in its central position by the link construction indicated in Figs. 6 and 7.

45 With the form of intermediate blade F shown in Figs. 5 and 6, instead of the slot N I provide a perforation W to receive the bolt or pivot pin C. The rearward extension O is provided with a slot f' adapted to receive a suitable filler-piece through which 50 passes a connecting or pivot pin X which likewise secures the links P and Q to the extension O.

As shown in Fig. 7, instead of slotting 55 the rearward extension O of the intermediate blade, I provide a collar R adapted to slide over the rearward extending portion O and having pivotally connected to it the links P and Q.

60 In the embodiments of my invention shown in Figs. 5, 6 and 7 the links described in connection with the intermediate blade serve merely to maintain the intermediate blade in central position relative to the outer blades; whereas, in the form of my inven-

tion shown in Fig. 1, the links serve not only this function, but they also serve as a part of the mechanism which causes the intermediate blade to move rearwardly relative to the coöperating outer blades.

70 It will readily be seen that either cutting blade a or b may be dispensed with and the blade F have either a regular or irregular cutting edge, as desired, which will coöperate with the cutting edge of the retained outer blade, so that when the cutting blades are forced toward each other the blade F will move longitudinally rearwardly toward the pivotal connection.

75 The improvements herein set forth are not 80 limited to the precise constructions and arrangements shown and described, as they may be embodied in various forms and modifications without departing from the spirit and scope of the invention.

85 What I claim is:

1. A cutting instrument of the class described, comprising two outer blade members, each of which is provided with a handle member, an intermediate blade member having a slot therein located between said outer blade members, all of said blade members being connected by a common pivot pin, and links pivotally-connected to the rearward end of the intermediate blade member and to the handle members of said outer blade members.

90 2. A cutting instrument of the class described having outer blade members and an intermediate blade member, all of which are 100 connected together by a common pivot pin, the intermediate blade member being provided with a slot through which the pivot pin passes and also having scalloped portions on its opposite edges, one of which 105 scalloped portions coöperates with the cutting portion of one of the outer blade members and the other scalloped portion coöperates with the cutting edge portion of the other outer blade member, and links connecting the handle portions of said outer blade members with the rearward portion of the intermediate blade member.

110 3. A cutting instrument of the class described, comprising a pair of outer blade members and an intermediate blade member, all of which are connected together by a common pivot pin, the intermediate blade member having scalloped cutting edges on 115 opposite edges thereof, one of which scalloped cutting edge coöperates with the cutting edge of one of the outer blade members and the other scalloped cutting edge coöperates with the cutting edge of the other outer blade member, the intermediate blade member having a closed slot within which 120 operates a slide piece through which passes the common pivot pin, and means comprising two links pivoted to the rearward end of said intermediate blade members, the 125 130

other ends of said links being pivoted respectively to the handle portions of the outer blade members to cause the intermediate blade member to move rearwardly or longitudinally with respect to the outer blade members as said outer blade members approach each other.

This specification signed and witnessed this 14th day of April, A. D. 1915.

WILLIAM P. ROBERTSON.
